CHRISTIAN SCHMITZ, OF PHILADELPHIA, PENNSYLVANIA

Letters Patent No. 87,298, dated February 23, 1869.

IMPROVED MACHINE FOR TANNING, FULLING, AND CLEANSING.

The Schedule referred to in these Letters Patent and making part of the same.

To all whom it may concern:

Be it known that I, CHRISTIAN SCHMITZ, of the city and county of Philadelphia, in the State of Pennsylvania, have invented a new and useful Machine for Fulling and Tanning Hides and Skins; and I do hereby declare the following to be a full, clear, and exact description of the same, sufficient to enable others skilled in the art to which my invention appertains, to fully understand and use the same, reference being had to the accompanying drawings, making part of this specification, and in which—

Figure 1 is a side elevation of my machine, one side of the framing being removed.

Figure 2 is a top view of the same, the rotary box being shown in section through the line x x , fig. 1.

Similar letters of reference indicate corresponding parts in both figures.

My invention has for its object to facilitate the process of fulling and tanning hides and skins by so constructing the machine as to produce a complete result in an unusually short time.

To effect these results, I mount diagonally upon a suitable frame-work a rhomboidal-shaped box, which contains the hides, and is rotated by suitable gearing, and having its sides, on their inner surface, provided with a number of projections.

This box is provided with journals, one of which is made hollow, to permit the introduction of water and steam, as will hereinafter be more fully described.

In the accompanying drawings—

A A represent a suitable frame-work for the support of a rhomboidal box, B.

This latter has journals, a a' , which rest upon the frame-work A.

I prefer to make this box B of oak wood, it being generally less porous than other wood, but it may be made of copper, lead, or any other non-corrosive metal.

To the sides of this box, on the interior thereof, I attach small pieces of wood, forming projections, c, as plainly shown in fig. 2.

These projections are bevelled or rounded on their outer surface, and have smooth sides, so as not to catch or take hold of the skins or hides.

In case heavy hides are to be treated, it would be advisable to insert pins between the projections c.

I prefer that these latter shall not be less than two inches in length, nor exceed six inches in height. They are arranged as shown in the drawing, and should be placed about six inches apart.

The object of these projecting pins and blocks is to allow the water or tanning-stuff to pass through, and also to assist in what is called "breaking" and softening the skins or hides.

In the sides of the box are openings, D, over each of which is placed a perforated metal plate.

These openings have covers, d.

The object of these openings is to let the fluid or

water run out during the process of tanning, or thereafter.

An opening, E, is made in one side of the box, to allow the introduction of the skins, as well as to facilitate the cleaning of the box.

A door, F, which, when closed by suitable means, (as covering the inside thereof with felting, rubber, or other water-proof material,) prevents the escape of the contents of the box, covers said opening.

One of the journals a' of the box is made hollow, and with it is connected a branch-pipe, a'' .

Through the journals, for instance, steam may be introduced, and simultaneously therewith water may be forced through the branch-pipe into the rotary box.

The operation is as follows:

The tanning-fluid and the hides to be treated are first introduced into the box B, and the door closed. Said box B is now set in motion by any suitable means. I have shown a cog-wheel, F¹, mounted upon one of the journals of the box, engaging with a pinion, G, on the axis of which is a fixed and a loose pulley, H H', respectively. A belt is placed over the fixed pulley, which shall receive motion in any convenient manner, by hand or other power, and communicates it to the box B. However, I do not confine myself to this peculiar mode of causing the revolution of the box, for, as before stated, other means may be substituted with, perhaps, equally good effect. During the revolution of the box, the hides therein contained are always in motion, on account of the peculiar form of the box, and thus the hides or skins are prevented from being thrown together. Thus each hide is thoroughly worked. Steam or water, or both, may be forced into the box, through the hollow journal and its branch, at any time during the operation.

After the hides have been sufficiently treated, the covers d are drawn away from the openings and the water is allowed to flow off.

The hides are then taken out from the box and are ready for the finishing-process.

This machine can also be used for greasing wax-skins or upper leather, which has been performed heretofore only by hand. In this case, as also in tanning, steam only is introduced into the box.

This machine can be used for all kinds of leather, whether tanned or untanned, with or without hair; and one of the prominent advantages of its use is the doing away with the inconveniences incident to the old way of fulling.

In the fulling-troughs now generally in use, the skins fall from the top to the bottom without making the whole revolution, really turning but one-half the distance, while by my invention the skins, being in constant motion, strike the six sides of the box, and are thereby completely turned, and are prevented from heaping together, as in the old mode. The work is thus done better, and also quicker and cheaper.

The simplicity, practicability, and usefulness of my machine are its main recommendations.

Having thus described my invention,

What I claim as new, and desire to secure by Letters Patent, is—

1. A rotary box, mounted diagonally on a framing, and having its sides, on the interior, provided with projections, substantially as herein shown and described, for the purposes specified.

2. Providing the rotary box with a hollow journal,

for the introduction of steam and water, substantially as herein described.

3. The machine for tanning, fulling, and cleansing, constructed and operating substantially as herein described.

To the above, I have signed, this 10th day of December, 1868.

Witnesses: CHRISTIAN SCHMITZ.
